UNITED STATES PATENT OFFICE.

JULIUS DISS, OF DUSSELDORF, PRUSSIA, GERMANY.

FIRE-ESCAPE.

SPECIFICATION forming part of Letters Patent No. 368,075, dated August 9, 1887.

Application filed May 26, 1886. Serial No. 203,310. (No model.) Patented in Germany March 13, 1886, No. 37,360, and in France May 10, 1886, No. 176,036.

To all whom it may concern:

Be it known that I, JULIUS DISS, engineer, subject of the Grand Duke of Baden, residing at Dusseldorf, Prussia, German Empire, have 5 invented certain new and useful Improvements in Fire-Escapes, (for which Letters Patent have been granted in France No. 176,036, dated May 10, 1886, and in Germany No. 37,360, dated March 13, 1886;) and I do hereby declare the following to be a full, clear, and exact description of the invention, such as will enable others skilled in the art to which it app pertains to make and use the same, reference being had to the accompanying drawings, and 15 to letters or figures of reference marked thereon, which form a part of this specification.

Referring to the drawings, Figures 1 and 2 are opposite side elevations; Fig. 3, an edge view, and Fig. 4 a vertical axial section, taken 20 on line $\alpha\alpha$ of Fig. 1, of my improved fire-escape. Fig. 5 shows the fire-escape contained in a casing for use as a pocket fire-escape.

This invention relates to that class of fire-escapes in which is employed a carriage or support for the person or other load constructed 25 to travel along a rope, and with which is combined a brake by means of which the speed of the carriage on the rope is regulated.

The invention consists in the construction of 30 the carriage and brake devices, and in the combination therewith of a case containing a rope-spool when the fire-escape is constructed to be carried on the person, substantially as herein-after fully described, and as specified in the 35 claims.

In the drawings, C indicates the carriage composed of a rectangular frame having a perforation, c^3 , in each of its end cross-bars, c^1 c^2 , the cross-bar c^2 being also provided with suitable means for attaching a support thereto for 40 the user or for suspending a load therefrom—as, for instance, two hooks, h h .

Any suitable device may be attached to or suspended from the hooks from which the user 45 is supported—as, for instance, a girt, or even a rope or other suitable support, which I have deemed unnecessary to show, as I do not desire to claim any specially-constructed support.

In the side bars or cheeks c c of the frame are 50 journaled cross-bars or rollers R and R', the

upper roll, R', being journaled in sliding bearings b' , fitted in slots c^4 , formed in the cheeks of the frame. r is the upper guide-roll and r' the lower guide-roll, which, together with the pin r^2 , that co-operates with the lower 55 guide-roll, r' , serve to guide the rope to and from the rolls R' R from and to the openings in the end bars, c c .

As shown, the rope A passes through the opening in the upper cross-bar, c' , thence alternately over and under the series of rolls to and between the lower guide-roll, r' , and the pin r^2 , and thence through the opening in the lower cross-bar, c^2 . The brake for regulating the speed at which the carriage C is to travel 65 along the rope comprises a lever, L, pivoted to the upper cross-bar, c' , of the frame, and a wedge-shaped and forked brake-shoe, S, pivoted to the lever and straddling and impinging 70 upon the rope A. 7c

It will be seen that if the lever L is pressed against the carriage the brake-shoe S not only presses the rope more or less tightly onto the guide-roll r , according to the pressure applied to the lever, but wedging between said guide-roll and the roll R', which, as stated above, is journaled in sliding bearings, depresses said roll, thereby wedging the rope between the said roll R' and the succeeding roll R, thereby regulating the speed with which the carriage 80 travels along the rope A.

The described device may be used for the lowering of any kind of materials from an elevation, and in such case an ordinary rope can be employed; but when used for the purposes 85 for which it is chiefly designed a wire rope is employed. The frame of the carriage C may be incased in leather and the casing or sheathing provided with hand-holes.

When the device is constructed to be carried on the person, I provide, as shown in Fig. 5, an inclosing-case, B, for the same, in which is journaled a rope-spool, the rope A being in this case made of fine steel wire, so that a very thin flexible rope capable of supporting a comparatively-heavy load and of great length may be wound on the spool. 90

One end of the rope is preferably secured to the spool and the other end, after being threaded through the carriage, has a loop, a, formed 95 100

thereon, so that it may be readily secured to any stationary object of sufficient strength to support the weight to be suspended from the carriage, or said rope end may be provided with any other suitable means for attaching it to a stationary object.

If a necessity arises for the use of the fire-escape, the carriage is removed from its case, the rope end *a* secured to some stationary support, and the case *B* thrown out of a window—for instance, through which the escape is to be made—thereby causing the rope to unwind from the spool. The carriage is now caused to slide along the rope to the outside of the window and the brake operated to prevent its sliding along the rope. The person now seats himself into the girt and then again manipulates the brake-lever to allow the carriage *C* to slide along the rope at the desired speed.

20. It will be understood that when the brake-lever is pressed close to the frame of the carriage the rope will be wedged to such an extent as to effectually prevent any movement of the carriage on the rope, whatever be the weight suspended therefrom, and in order to allow said carriage to travel along the rope the lever has to be forcibly moved outward to withdraw the wedge-shaped brake-shoe from between the guide-roll *r* and the roll *R'*.

30. Having now described my invention, what I claim is—

1. In a fire escape, the combination of a carriage consisting of a series of cross-bars or rolls journaled in a frame provided with means for suspending a load therefrom, a rope passing

alternately over and under the rollers, a brake consisting of a lever pivoted to the carriage-frame, and a forked brake-shoe straddling the rope between two of the rolls, substantially as and for the purpose specified.

2. In a fire-escape, the combination of a carriage consisting of a series of cross-bars or rollers journaled in a frame provided with means for suspending a load therefrom, one of said rollers being journaled in sliding bearings, a brake consisting of a lever pivoted to the carriage-frame, and a wedge-shaped and forked brake-shoe straddling the rope between the roller having the sliding bearings and one of the other rollers, substantially as and for the purpose specified.

3. The herein-described pocket fire-escape, comprising a carriage consisting of a series of rollers journaled in a frame provided with means for suspending a load therefrom, a rope passing alternately over and under the rollers, a brake consisting of a lever pivoted to the carriage-frame, and a forked brake-shoe connected with the lever and straddling the rope between two of the rollers, in combination with an inclosing-easing for containing the fire-escape, and a spool journaled in said easing upon which the rope is wound, substantially as and for the purposes specified.

In testimony whereof I affix my signature in presence of two witnesses.

JULIUS DISS.
